UNITED STATES PATENT OFFICE.

ABEL T. ATHERTON, OF LOWELL, MASSACHUSETTS.

LOOM-SHUTTLE.

SPECIFICATION forming part of Letters Patent No. 314,907, dated March 31, 1885.

Application filed June 7, 1884. (No model.)

To all whom it may concern:

Be it known that I, ABEL T. ATHERTON, of Lowell, in the State of Massachusetts, have invented a certain new and useful Improvement in Loom-Shuttles, of which the following is a specification.

My invention relates to loom-shuttles of the kind known as "hand-threading" shuttles, or, as they are sometimes but improperly called, "self-threading" shuttles. In a shuttle of this kind the yarn from the spindle passes to the throat, in which there is usually a stud or shoulder in line with the axis of the spindle, around which shoulder the yarn makes a quarter-turn, and thence passes to and through the delivery-eye in the side of the shuttle. When the shuttle is in active operation, the thread or yarn is liable to leave the shoulder or stud and to come to the outside of the shuttle, thus producing what is called "unthreading," the result of which is to make a bad place in the cloth, and to necessitate the stopping of the loom for the purpose of replacing the yarn in its proper position.

It is my object to prevent unthreading, without, however, interfering with the easy threading of the shuttle. To this end I close the passage in the top of the shuttle through which the thread or yarn from the spindle is passed over and around the shoulder or stud by a spring which is so arranged that it will yield to permit the entrance of the thread into the passage guarded by it, and will, after the thread has entered, automatically close and prevent the accidental displacement of the thread from around the shoulder.

The nature of my invention will be readily understood by reference to the accompanying drawings, in which I have represented it as applied to a hand-threading loom-shuttle of the kind described in Letters Patent No. 185,041, of December 5, 1876, granted to Whitehead & Atherton, assignees of A. M. Moore.

Figure 1 is a side elevation of the front portion of the shuttle. Fig. 2 is a plan of the same. Fig. 3 is a cross-section on line 33, Fig. 1. Fig. 4 is a longitudinal section on line 44, Fig. 2.

A is the body of the shuttle, B is the spindle, C is the chamber, and D is the throat. G is the delivery-eye, H is the threading-eye in

the wall of chamber C, and K is the narrow threading-slot, which extends longitudinally from the delivery-eye G to the threading-eye H, and also extends laterally through from the outside of the shuttle into the throat D. E is the stud or shoulder, fastened in place in the throat by its base-piece E', so as to be out of contact with the side and front walls thereof, thus leaving on the sides and at the front of the stud or shoulder passages a b c, which are used during the threading operation in the manner hereinafter explained. In the threaded shuttle the thread or yarn extends from the end of the spindle to the stud or shoulder E, around the front of which in the passage a it makes a quarter-turn, and thence passes to and out through the delivery-eye G.

Thus far the shuttle is substantially like the patented shuttle hereinbefore referred to.

As I have before stated, the thread or yarn, when the shuttle is in active operation, is apt to rise and escape from the stud or shoulder through the passage a, which ordinarily is open at the top. This event is of not infrequent occurrence, even in the patented shuttle represented in Letters Patent hereinbefore cited, although in said patented shuttle it was essayed to prevent such an accident by bending the upper end of the stud forward and downward until it almost touched the wood at the shallow end of the throat.

I have found in practice that to prevent with certainty the yarn from flying off from the stud, and thus coming to the outside of the shuttle, it is requisite to completely close the outlet through which the yarn may escape at the point where it turns the corner to go to the delivery-eye. To this end I make use of a light plate-spring, d, which is arranged to completely close at the top the opening or passage between the shoulder or stud and the front wall of the throat. The spring for this purpose may be variously arranged. In the arrangement shown in the drawings it is secured to the top of the stud or shoulder E, and its free end spans the space intervening between the part E and the front wall of the throat, and bears or presses upon the shuttle-wood in a slight recess or depression, e, formed in the top of the shuttle. Under this arrangement unthreading is entirely prevented. At the same time the op-

eration of threading the shuttle by hand can be performed with as much ease and expedition as though the spring were not present.

The threading operation is as follows: The 5 cop-yarn from the spindle is pressed by the forefinger of the right hand through the threading-eye, and the projecting end is taken in the left hand. The thread, held on the inside in the right hand and on the outside in the left hand, 10 is drawn along through the threading-slot K, as indicated by dotted line *xx*, Fig. 2, being bent up as it reaches the stud E, so as to pass along through the passage *b* between the latter and the adjoining side wall of the throat, as 15 indicated by dotted lines *xx*, Fig. 3. From the threading-slot the thread emerges into the delivery-eye. As soon as this occurs, the inner bent-up end of the thread (held in the right hand) is drawn down into the depression *e* and 20 under the free end of spring *d*, which yields and rises to permit the passage of the thread. The thread is now in the passage *a*, and extends directly from the end of the spindle around the corner formed by the stud or shoulder *E* to and 25 through the delivery-eye *G*. The operation can be performed quickly and with as much ease as though there were no spring present.

In conclusion I state that I am aware it is 30 not new in a hand-threading shuttle to close the threading-slot—that is to say, the slot formed in the wood or body of the shuttle and communicating with the delivery-eye for the purpose of facilitating the entrance of the

thread into the delivery-eye—by a spring-controlled plug or equivalent device operating 35 automatically to close the threading-slot after the passage therethrough of the yarn or thread. This is not my invention, nor does it serve to bring about the result which it is the object of my improvement to attain.

What I claim as new and of my own invention is—

1. The combination, with the shuttle-body formed with a delivery-eye, and the shoulder or stud around the corner formed by which the 40 thread or yarn from the spindle passes to the delivery-eye, of a spring-controlled strip bridging the space through which the thread passes between said stud or shoulder and shuttle-body, adapted to yield to the thread as the latter is drawn under it into said space and to automatically close after the passage of the thread, substantially as and for the purposes hereinbefore set forth.

2. The combination, with the shuttle-body 45 formed with delivery-eye *G*, threading-slot *K*, threading-eye *H*, and throat *D*, of the stud or shoulder *E* and spring-strip *d*, under the arrangement and for joint operation substantially as hereinbefore shown and described.

In testimony whereof I have hereunto set my hand this 2d day of June, 1884.

ABEL T. ATHERTON.
